PRECAST FIREBOX

Elwood C. Lewis, Philadelphia, Pa.

Application October 31, 1940; Serial No. 363,627

3 Claims. (Cl. 158—1.)

In connection with the installation of oil burners in domestic or industrial heating systems; and more especially in connection with "conversion jobs," that is, instances in which an ordinary coal burning furnace is to be converted to receive an oil burner, it is necessary to build a refractory lining in the ash pit and the lower part of the combustion chamber so that the flame of the oil burner is effectively surrounded by the refractory material and prevented from contacting the metal walls of the furnace proper or the water jacket which sometimes forms a part of the furnace. Such refractory lining has, until relatively recently, been produced by building the desired wall or lining from individual bricks made of the desired refractory material and secured together with refractory cement. This involved considerable time and labor and, with the ordinary type of bricks, it was practically impossible to produce the very desirable "streamlined" contour.

As an improvement on this general practice it has been suggested to pre-cast wall sections of predetermined contour by means of which a fire box or combustion chamber lining could be built. This type of construction is perhaps best exemplified in the Eisentrager Patent No. 2,075,433.

My invention relates to an improved form of pre-cast fire box, the construction and advantages of which will be more clearly understood from the following specification and the accompanying drawing in which:

Fig. 1 represents a top plan view of a pre-cast fire box embodying my invention.

Fig. 2 represents a front elevation of Fig. 1.

Figs. 3 to 7 inclusive represent perspective views of the sections from which my novel pre-cast fire box is built.

Referring to the drawing in which like reference characters indicate like parts, and more particularly to Figs. 6 and 7, it will be seen that I utilize two identical and symmetrical pre-cast bottom sections A and B each of which consists of the flat bottom surface 8, the vertical, inner abutting edges 10, the front, vertical walls 12 and the outer side walls 14. Each of the bottom sections A and B is dished as at 16 so as to leave a bottom or base of a predetermined thickness and a vertical wall 20 also of a predetermined thickness, it being noted that the vertical wall 20 terminates in the slightly thicker front wall portion 22. From Figs. 1, 6 and 7 it will be seen that the bottom sections A and B

have a curvilinear contour of a generally oval or pear shape form when assembled.

Referring to Fig. 4 I have shown a perspective view of the back wall section forming part of my invention and which consists of the curved, vertical wall 24 which is of the same thickness as the vertical wall 20 of the sections A and B and which is adapted to be positioned over the rear, curved portions of the sections A and B as shown in Fig. 1. When assembled, the bottom 21 of the back, curved wall section 24 overlaps the abutting rear portions of the sections A and B to the extent X—X so that, when the rear, curved wall 24 is set vertically and cemented in position, it also overlaps and serves to hold together the abutting edges of the bottom sections A and B. As will be seen from Figs. 1 and 4, the back wall section 24 is provided with an overhanging flange or visor 26 for a purpose hereinafter described.

In Fig. 3 I have shown an outside perspective view of one of the side wall sections C, and in Fig. 5 I have shown an inside perspective view of the similar side wall section D. Referring more specifically to Figs. 3 and 5, it will be seen that the side wall sections C and D each comprise a vertical, curvilinear wall 28 and a front, angularly disposed wall 30, it being noted that the thickness and curvature or the contour of the side wall sections C and D correspond to the thickness, shape and contour of the portions X—Y, X—Y of the bottom sections A and B. After the sections A and B have been cemented together in abutting position and the rear section 24 has also been cemented in position, the side walls C and D are placed over the bottom sections A and B with the rear edges 32 of the side sections C and D abutting against the edges 34 of the rear section 24; and with the bottom edges 36 and 38 of the side sections C and D resting on the walls 20 and 22 of the sections A and B. The sections C and D are of course cemented to the rear section 24 and the bottom sections A and B. It will be noted that the front walls 30 of the side sections C and D are molded with arcuate openings 40 which merge into the straight walls 42 so that, when the parts are all assembled (and as will be seen from the front elevational view of Fig. 2) an arched opening is produced through which the barrel of the oil burner is adapted to be inserted. It will be noted that the straight edges 22 of the sections A and B constitute the "floor" of the arched opening so that the barrel of the oil burner can be rested on the front edges 22. In this connec-

tion it is pointed out that the oil burner is usually set at about seven inches from the floor and I therefore make the vertical height of the walls 12 and 20 of seven inches or of any desired height at which it is desired to set the burner. After the barrel has been inserted and set as suggested, any clearance between it and the wall of the arched opening is of course plugged up with refractory cement.

As will be clearly seen from Figs. 1, 6 and 7, my pre-cast fire box presents an entirely streamlined, internal contour free from all angles or corners whatever thus preventing the carbonization which results from the deposit of carbon in inaccessible and relatively cooler corners which would be present in a structure formed of bricks or of other pre-cast sectional formations which do not present the same continuous, internal, streamlined contour. It will also be noted that the oval shape provides a relatively large space at the center and rear of the fire box toward which the flame is directed, and that it provides a relatively restricted front area so that, after the flame is reflected by the rear wall 24, the heat, as well as the flame itself, are evenly distributed. The overhanging flange 26 serves as a baffle or deflector and causes the flame, which hits the rear wall 24, to roll or curve back upon itself in the direction of the narrow, front portion of the fire box. The sections A and B serve as a streamlined flooring for the fire box so that any uncombusted drippings or fuel which may collect when the burner fails to ignite or when the ignition ceases before the oil burner pump stops functioning will not be allowed to seep into inaccessible corners where the fuel can carbonize but will, on the contrary, be maintained in the smooth, rounded, dished portion of the sections A and B so that, when the burner is lighted again and the heat attains the necessary degree, such drippings will burn completely and leave no soot or carbon. Also, the thickness of the base portions or bottoms of the sections A and B form an insulation between the heat and the floor thus preventing loss of heat by conduction and the dished contour 16 serves to reflect the heat upwardly more effectively than would be the case if the bottom of the fire box were flat.

Having thus described my invention, what I claim as new and desire to secure by Letters Patent is:

1. A pre-cast fire box comprising a base section of a generally forwardly tapering pear shaped formation and having a bottom and a vertical wall, said vertical wall being curvilinear throughout its major portion and having a straight front portion, a back section adapted to rest upon the rear portion of the vertical wall of said base section and comprising a vertical wall of a curvature corresponding to the curvature of said rear portion and an upper forwardly over-

hanging flange, and a pair of side sections adapted to rest on the remaining opposite portions of said base section, each of said side sections comprising a curved vertical wall conforming to the curvature of the corresponding portion of the vertical wall of said base section and a straight front wall corresponding to the straight portion of said base section, the lower juxtaposed portions of the straight front walls of said side section being cut away whereby an opening is formed at the junction of said straight front walls with each other and with the straight portions of said base section.

2. A pre-cast fire box comprising a dished base section of a generally forwardly tapering pear shaped formation and having a generally concave bottom and a vertical wall, said vertical wall being curvilinear throughout its major portion and having a straight front portion, a back section adapted to rest upon the rear portion of the vertical wall of said base section and comprising a vertical wall of a curvature corresponding to the curvature of said rear portion and an upper forwardly overhanging flange, and a pair of side sections adapted to rest on the remaining opposite portions of said base section, each of said side sections comprising a curved vertical wall conforming to the curvature of the corresponding portion of the vertical wall of said base section and a straight front wall corresponding to the straight portion of said base section, the lower juxtaposed portions of the straight front walls of said side section being cut away whereby an opening is formed at the junction of said straight front walls with each other and with the straight portions of said base section.

3. A pre-cast fire box comprising two symmetrical parts which, when assembled in abutting position, produce a generally forwardly tapering pear shaped base section having a dished bottom and a vertical wall, said vertical wall being curvilinear throughout its major portion and having an angularly disposed straight front portion, a back section adapted to straddle the abutting rear portions of the vertical walls of said base section and comprising a correspondingly curved vertical wall and an upper forwardly overhanging flange, and a pair of side sections adapted to rest on the remaining portions of said base section, each of said side sections comprising a vertical wall conforming to the curvature of the corresponding portion of the vertical wall of said base section and an angularly disposed straight front wall adapted to rest on the front straight wall of said base section, the lower juxtaposed portions of the straight front walls of said side sections being cut away whereby an opening is formed at the junction of said straight front walls with each other and with the straight portions of said base sections.

ELWOOD C. LEWIS.
